SAMUEL N. HALL, OF HOUSTON, TEXAS.

BIT-BRACE.

1,107,938.

Specification of Letters Patent. Patented Aug. 18, 1914.

Application filed November 17, 1913. Serial No. 801,559.

To all whom it may concern:

Be it known that I, SAMUEL N. HALL, citizen of the United States, residing at Houston, in the county of Harris and State of Texas, have invented certain new and useful Improvements in Bit-Braces, of which the following is a specification.

This invention relates to new and useful improvements in bit braces.

10 The object of the invention is to provide a brace of the character described, adapted to be used in the ordinary manner and also equipped with a crank arm which is secured to the bit chuck and which has an adjustable handle, whereby said chuck may be rotated while the brace remains stationary. In case 15 a bit of small size is used, it is often desirable to rotate the same rapidly and small leverage is required to rotate the same and 20 in such case the handle of the crank arm may be adjusted so as to bring the same close to the chuck and a more rapid rotation of the bit can thus be accomplished.

25 A further feature of the invention resides in the provision of an improved form of handle, which is carried by the crank arm and which may be readily adjusted on the stock of the brace and used as a handle therefor when the brace is used in the ordinary manner.

30 Another feature of the invention resides in the provision of a grip, whereby the brace stock may be held in steady position while the bit is being rotated by means of the adjustable crank arm.

35 With the above and other objects in view, the invention has particular relation to certain novel features of construction, operation and arrangement of parts, an example 40 of which is given in this specification and illustrated in the accompanying drawings, wherein,

Figure 1 is a side elevation of the complete device, shown partially in section. Fig. 2 shows a side elevation of the adjustable handle of the crank arm. Fig. 3 shows an end view thereof. Fig. 4 shows a plan view of the crank arm and adjustable handle. Fig. 5 shows a plan view of the crank arm handle. Fig. 6 shows an end view thereof, and Fig. 7 shows a plan view of the crank arm, partially in section, showing the method of its attachment to the chuck.

Referring now more particularly to the drawings, wherein like numerals of reference designate similar parts in each of the

figures, the numeral 1 refers to the stock of the brace, which, in general contour, is of the usual and well known form. One end of this stock has the breast piece 2 which is 60 rotatable relative to the stock and the other end of the stock carries the bearing member 3 in which the chuck 4 rotates. The outer end of this chuck is arranged to receive the bit 5 and is of the usual and well known construction, and the inner end thereof is reduced and projects through the bearing 3, and also through one end of the crank arm 6. Said end of the crank arm 6 is enlarged and bifurcated, forming flat fingers 7, 7, 70 having alined orifices through which the reduced end of the chuck extends and fixed on said reduced end and between said fingers is the ratchet wheel 8, the purpose of which will be hereinafter set forth. This crank 75 arm is a tubular member of the desired length and its free end carries a handle supporting member 9 which may be adjusted on said arm, as will be hereinafter described, so as to adjust the position of the handle 80 relative to the chuck. When a small bit is being used and it is desired to rotate the same rapidly, the handle may be adjusted on the arm 6, so as to bring it close to the chuck, as shown in dotted lines in Fig. 1, but when 85 a large bit is in use, and it is necessary to rotate the same slowly, said handle may be adjusted so as to give more leverage, or it may be brought into the position shown by heavy lines in Fig. 1, and the device thus 90 used in the manner of the ordinary brace, said crank arm handle acting as a handle for the brace, being specially constructed for that purpose, which special construction will now be described.

95 One end of the crank arm 6, as hereinbefore explained, has the handle supporting member 9, which is semi-tubular in shape, being deeply grooved from end to end. This member serves as a support for the handle 100 10. This handle is formed in two sections, as shown in Figs. 5 and 6, said sections being hinged together at one side by means of the hinges 11 and 12, so that the handle may be readily opened and passed over the handle 105 supporting member 9 and the stock 1 of the brace, as shown in Fig. 1 and when in this position, said stock will rest in the groove of the member 9. The hinge 12 has a coil spring 13 which surrounds the pintle of said 110 hinge and whose free ends projects out each way and press against the sides of said hinge

and normally tend to hold said handle in its closed position. The members forming the hinge 12 are extended outwardly, as shown in Fig. 6, so that they may be readily grasped and when pressed together will operate to open the handle, so that it may be removed from or placed on the stock with ease.

One end of the handle supporting member 9 carries a bearing member 14 through which the free end of the crank arm 6 slides and a thumb screw 15 is screwed through a tapped hole in one side of the bearing member 14 and its inner end is adapted to project against said arm, and by means of this screw, the handle may be fixed in any desired position on the crank arm.

Arranged between the fingers 7, 7 on each side are two dogs 16 and 17, which are pivoted to said fingers and extending across the bottom of said slot between the fingers is an oblong plate 18, which rests against the inner end of said dogs. The end of the arm 6 has an internal socket 19 alined with the slot between the fingers in which is seated a coil spring 20, which presses against the plate 18 and which surrounds a stud 21 depending from the central portion of the plate 18. The pressure of said spring holds the plate 18 against the inner ends of the dogs 16 and 17 and operates to hold said dogs in engagement with the ratchet wheel 8, one on each side, said dogs serving to lock the chuck 4 against rotation relative to the arm 6. In use, the brace must often be held in such a position that a complete rotation of the crank arm 6 is impossible and the hole must be bored by successive partial rotations of the bit. In such cases, one of the dogs, as 16, is withdrawn, so that when the crank arm is given a partial turn in one direction, the chuck and bit will also be turned, but as brought back to its original position, the chuck will remain stationary, the dog 17 slipping over the teeth of the ratchet wheel 8, and engaging therewith only when another forward turn is imparted to the crank arm.

The invention presents a simple, efficient

and economical bit brace whereby the speed 50 of rotation, or leverage, of the chuck may be easily increased or decreased to suit the work to be performed; it being pointed out that the manipulating handle and its sleeve may be entirely removed from and reversed upon 55 the crank arm to further reduce the leverage as will be readily appreciated.

What I claim is:—

1. The combination with a bit stock having a chuck whose inner end projects 60 beyond its bearing in the stock, of a member secured to the projecting end of said chuck, and radially adjustable means carried by said member for rotating said chuck independently of said stock. 65

2. The combination, with a bit stock having a chuck, of a member, having an independent operative connection with said chuck, and means carried by and adapted for reversal upon said member, said member being so formed that it affords different degrees of leverage by such reversal, for rotating said chuck independently of said stock. 70

3. The combination, with a bit stock having a chuck, the inner end of which projects beyond its bearing in the stock, of a member secured to the projecting end of said chuck, and radially adjustable means carried by said member for rotating said chuck independently of said stock and reversible thereon to further vary the leverage. 75

4. The combination with a bit stock having a chuck, of an arm having an operative connection with said chuck, a sleeve adjustably carried by said arm, said sleeve having a longitudinal groove within which the stock is adapted to seat, and a handle comprising hinged sections adapted to encompass said sleeve and stock for rotating said chuck. 80 85 90

In testimony whereof I have signed my name to this specification in the presence of two subscribing witnesses.

SAMUEL N. HALL.
